Inventor:
Edward B. Allen
by Crosby & Gregory, Atlys.

UNITED STATES PATENT OFFICE.

EDWARD B. ALLEN, OF PORTLAND, MAINE, ASSIGNOR TO JAMES W. BROOKS, TRUSTEE, OF CAMBRIDGE, MASSACHUSETTS.

BURNISHING-MACHINE.

SPECIFICATION forming part of Letters Patent No. 374,885, dated December 13, 1887.

Application filed August 15, 1887. Serial No. 216,995. (No model.)

To all whom it may concern:

Be it known that I, EDWARD B. ALLEN, of Portland, county of Cumberland, and State of Maine, have invented an Improvement in 5 Machines for Burnishing and Beading Boots or Shoes, of which the following description, in connection with the accompanying drawings, is a specification, like letters on the drawings representing like parts.

10 This invention relates to machines for burnishing heels of boots or shoes, and has for one of its objects to provide a burnishing-machine with a beading-tool adapted to be operated from the shaft which actuates the burnishing-tool, thereby effecting a considerable saving in time and labor.

My invention also has for its object to simplify and improve the construction of burnishing-machines.

15 The particular features in which my invention consists will be pointed out in the claims at the end of this specification.

Figure 1 is an elevation of a burnishing and beading machine constructed in accordance 20 with my invention; Fig. 2, a top view of part of the machine, showing the beading and burnishing tools and the disk or guideway for the burnishing-tool; Figs. 3 and 4, details to be referred to, and Fig. 5 a diagram to more 25 clearly show the positions of the burnishing and beading tools.

The frame-work of the machine, herein shown as a hollow upright or standard, a , resting upon a suitable base, a' , is provided at its 30 upper end with a bracket, a^2 , having bearings a^3 for a shaft, a^4 , the latter being movable longitudinally on said bearings, as will be described.

The shaft a^4 has mounted upon it a pinion, 35 a^5 , in mesh with a rack, a^6 , movable in guides a^7 , secured, as shown, to the said bracket, the said pinion being of considerable length to enable the shaft to be moved longitudinally and yet have the said pinion in engagement with the rack.

The rack a^6 has connected to or forming part of it a link or bar, a^8 , (shown in dotted lines, Fig. 1,) pivoted, as shown, at a^9 , to the forked end of a rod, b , having a stud, b' , extended 40 into a slot in a disk, b^2 , on the main or driving

shaft b^3 , supported in suitable bearings and provided, as shown, with a fast and loose belt-pulley, b^4 b^5 , rotation of the main shaft imparting an oscillating or rocking movement to the shaft a^4 through the rack and pinion and connecting mechanism described. 55

The shaft a^4 at one side of the machine, as herein shown, is provided with a grooved hub or collar, b^6 , and in the groove of which is fitted a stud, b^7 , herein shown as secured to a sliding box, b^8 , embraced by the forked end of the arm b^9 of a lever pivoted at b^{10} to the frame of the machine, the other arm, b^{12} , (shown by dotted lines, Fig. 1,) being connected, as shown, by a link, b^{13} , to a foot-treadle, b^{14} . The shaft 60 a^4 between the collar b^6 and the bearing a^3 , as herein shown, is encircled by a spring, c , which is compressed when the said shaft is moved longitudinally in one direction by depressing the treadle b^{14} . 70

The shaft a^4 at the opposite side of the machine has secured to it, as herein shown, a disk, c' , provided with a guideway in its face to receive a block, c^2 , (see Fig. 2,) movable up and down in said guideway. The block c^2 has secured to or forming part of it a burnishing-tool, c^3 , of ordinary construction. 75

The disk c' , block c^2 , and burnishing-tool c^3 are each provided with a slot, as shown by dotted lines, Fig. 1, through which is extended, as shown, one arm, c^4 , of an elbow-lever pivoted at c^5 to ears c^6 on the rear side of the disk c' . The arm c^4 is pivoted, as shown, to ears c^7 on a beading-tool, c^8 , fitted to and movable in a guideway formed in the face of 85 the burnishing-tool, as shown in Fig. 2, and by dotted lines, Fig. 1. The other arm, c^9 , of the elbow-lever referred to is forked at its ends, and the forked ends are provided with studs d , extended into a groove, d' , (see Fig. 90 3,) on a hub or collar, d^2 , loosely mounted on the shaft a^4 .

The beading-tool c^8 is moved up and down in the guideway in the burnishing-tool through the elbow-lever referred to by means of a lever, d^3 , pivoted, as shown, to a lug, d^4 , on the bracket a^2 , the said lever d^3 having one end forked, and each fork provided with a stud, d^5 , extended into a groove, d^6 , (see Fig. 3,) of the collar d^2 , the said lever having a handle, d^7 . 95 100

The burnishing-tool c^3 and beading-tool c^8 are brought in contact with and removed from the heel e^x of a boot or shoe, e , secured on a jack, e' , of ordinary construction, supported by a bracket, e^2 , attached to the upright a , by moving the handle d^7 in one or the other direction.

The burnishing-tool c^3 and beading-tool c^8 are shown in Fig. 1 in their lowest position, and the boot or shoe having been jacked in usual manner, the operator presses upon the treadle b^{14} , moving the shaft a^4 and the parts connected therewith toward the right in the direction of arrow 20.

In order to clear the jack when the shaft a^4 is moved to the right, and at the same time bring the burnishing-tool above and in line with the heel of the boot or shoe, the handle d^7 is moved in the direction of arrow 21 from its normal or full-line position marked 2 (see Fig. 5) to the dotted line position marked 3.

The burnishing-tool is brought into engagement with the heel of the boot or shoe by moving the handle d^7 to the dotted-line position marked 4, and it is held in said position by the operator until the heel is burnished, or it may be locked in any suitable manner, a spring, 5, pressing upon the said tool in usual manner. After the heel has been burnished, a stop or gage, shown as a rod, f , extended through a slide, f' , (see dotted lines, Fig. 1,) movable in a guideway in the upper face of a bracket, f^2 , secured to the standard a , is raised up behind and in the path of movement 30 of the disk c' . The stop or gage f is raised up and down and at the same time the slide f' is moved in its guideway, as herein shown, by moving the handle f^x of a lever pivoted, as shown, at f^3 to the bracket f^2 , one arm, f^4 , of 35 the said lever having a slot, f^5 , through which is extended a stud, f^6 , on the end of the rod f . The beading-tool, being in the position marked 7 above and in line with the heel-seat, is brought in contact with the said heel-seat by moving the handle d^7 from the position marked 4 to the 40 position marked 2. After the boot or shoe has been beaded, the operator releases the handle d^7 and f^x and removes the pressure from the treadle b^{14} , thus permitting the spring

c to move the shaft a^4 and parts connected 50 to it away from the jack and into the position shown in Fig. 1.

I claim—

1. In the herein-described burnishing-machine, an oscillating or rocking shaft, a burnishing-tool connected to one end of and oscillated by the said shaft, and mechanism to oscillate or rock said shaft, combined with mechanism, substantially as described, to move said shaft longitudinally, as and for the purpose specified.

2. In the herein-described burnishing-machine, an oscillating or rocking shaft and a burnishing-tool connected to and oscillated by the said shaft, combined with a lever operatively connected to the said burnishing-tool to reciprocate it independent of the shaft, substantially as and for the purpose specified.

3. The combination, in the herein-described burnishing-machine, of an oscillating shaft, a burnishing-tool, and a beading-tool connected with and oscillated together by the said shaft, substantially as described.

4. In a burnishing-machine, an oscillating shaft, a movable collar, d^2 , thereon, a burnishing-tool, c^3 , a beading-tool, c^8 , and a lever operatively connected, as described, to the beading and burnishing tools and to the collar d^2 , combined with a lever, d^3 , connected to the collar d^2 to move it longitudinally on the shaft, and thereby reciprocate the said burnishing and beading tools, substantially as described.

5. The oscillating disk or plate c' , the burnishing tool adapted to slide therein, and the beading-tool adapted to slide in the burnishing tool, substantially as described.

6. The burnishing-tool and the beading-tool, combined with a stop to keep the burnishing-tool above and in line with the heel, and a lever to cause the beading-tool only to be forced 90 against the heel, substantially as described.

In testimony whereof I have signed my name to this specification in the presence of two subscribing witnesses.

EDWARD B. ALLEN.
